[57] **ABSTRACT**

A water conserving apparatus designed particularly for use on recreational vehicles where a limited water supply is available, the apparatus includes a valved bypass line connected to the hot water line to return the water located within the remote end of the hot water line to downstream of the water heater.

7 Claims, 2 Drawing Figures

PATENTED DEC. 4 1973

3,776,261

WATER CONSERVING APPARATUS

BACKGROUND OF THE INVENTION

Recreational vehicles contain a reservoir tank of fresh water in order to supply the outlets within the recreational vehicle. The conventional form of recreational vehicles have at least one cold water outlet and one hot water outlet. The water is heated through a type of water heating apparatus which is also located within the recreational vehicle. In larger sized recreational vehicles there may be as many as two or three hot and cold water outlets.

When a person desires hot water, the person normally actuates the valve which is connected to the hot water line with the water being discharged therefrom. Normally, the hot water faucet is located at some distance from the water heater and if it has been a few minutes from the last time that hot water was drawn from the faucet, the initial flow of water will be quite cool. The normal procedure is for the person to discharge the initial cool water into a drain and then to make use of the subsequent flow of hot water. The wait for the water to turn hot is often quite annoying, and also the sudden advent of hot water after substantial flow of relatively cold water can be quite discomforting such as in a shower.

It is not uncommon for the amount of cold water located within the remote end of the hot water line to be one quart or greater in volume. A normal supply reservoir for such a vehicle would be forty gallons. This means that whenever a person desires to use hot water, a significant portion of the overall water supply is lost because that water is not heated. It is readily apparent that if this lost water be conserved, more water would be available for use and also the time in between refillings of the reservoir will be lengthened.

SUMMARY OF THE INVENTION

The water conserving apparatus of this invention is designed to be employed in combination with a conventional water supply system within a recreational vehicle. The conventional water supply system includes a reservoir which is adapted to contain a limited supply of water. This water is to be removed from the reservoir by a pump which in turn conducts the water either into a water heater or into a cold water supply line. The cold water supply line is connected to a faucet assembly within the recreational vehicle to supply the water for use. The water is conducted from the hot water heater into a hot water supply line which is connected to a second faucet assembly to supply the hot water for use. A by-pass line is connected to the hot water supply line adjacent the faucet assembly. The by-pass line is to conduct fluid from the hot water line and return such downstream of the water heater. The purpose of the by-pass line is to run off the portion of the water upstream of the water heater which is located within the hot water supply line and conduct such back into the system to be reheated. Therefore, when a person thereafter activates a hot water faucet, instant hot water is discharged therefrom.

BRIEF DESCRIPTION OF THE DRAWINGS

FIG. 1 is a schematic view of the water conservation apparatus of this invention; and

FIG. 2 is a cross-sectional view through an illustrated form of valve which is employed within the apparatus of this invention.

DETAILED DESCRIPTION OF THE SHOWN EMBODIMENT

Referring particularly to the drawing, there is shown in FIG. 1 a water reservoir 10 which is to retain a given quantity of water. A connecting line 12 is connected to the reservoir 10 and is adapted to receive the water from the reservoir 10. The free end of the connecting line 12 is connected to a pump 14. The structure of the pump 14 forms no direct part of this invention and is deemed to be conventional. The pump 14 is connected to an output line 16 which in turn is connected to a switching apparatus 18. The switching apparatus 18 is to activate the pumping apparatus at any time the pressure within the overall system drops below a predetermined level. Such switching apparatuses are deemed to be conventional and need not be described here in detail. The output line 16 extends through the switching apparatus 18 to the water heater 20. The water heater 20 is deemed to be a conventional type of water heater and again need not be described here in detail.

Within the output line 16, which is located in between the water heater 20 and the switching apparatus 18, a cold water supply line 22 is connected. Cold water supply line 22 is shown to supply water to a plurality of faucets 24, 26 and 28. It is to be understood that the faucets 24, 26 and 28 are conventional in construction and are to be manually actuatable in a conventional manner.

For purposes of description it is envisioned that the apparatus of this invention will be employed within a recreational vehicle, not shown. The faucet 24 is to be located in a kitchen sink fixture 30 with the faucet 26 located within a shower 32 and the faucet 28 located within a wash basin 34. However, it is to be understood that the showing of the three separate fixtures 30, 32 and 34 is merely for purposes of illustration and it is not intended to limit the use of the apparatus of this invention within a three-fixture type of installation. The apparatus of this invention could be employed in a one-fixture installation as well as a 10-fixture installation. Additionally, although the apparatus of this invention has been found to be particularly advantageous within a recreational vehicle which employs a limited water capacity, it is envisioned that the apparatus of this invention could be readily employed in other environments wherever there is a limited water supply. Actually, it is not even necessary to use the apparatus of this invention in a limited water supply environment. Wherever in any environment it is desired to conserve water, the apparatus of this invention would be particularly useful. However, the apparatus of this invention is to be employed in demand type of water systems, in other words, a water system which uses a pump and not a system which pressurizes the reservoir.

Connected to the water heater 20 is the hot water supply line 36. The hot water supply line 36 is to supply hot water to faucets 38, 40 and 42. The faucets 38, 40 and 42 are to be normally constructed similar to the construction of the previously mentioned faucets 24, 26 and 28. The hot water supply line 36 includes branch conduits 44, 46 and 48. The branch conduit 44 mates to faucet 38 with branch conduit 46 leading to faucet 40 and branch conduit 48 leads to faucet 42.

Connected within the branch conduit 44 adjacent faucet 38 is a by-pass line 50. In a similar manner, connected within the branch conduit 46 adjacent faucet 40 is a by-pass line 52, and connected within the branch conduit 48 adjacent faucet 42 is a by-pass conduit 54. The by-pass conduits 50, 52 and 54 are basically similar in construction and are all connected to a main by-pass line 56. A valve 58 is located within the by-pass line 50 in close proximity to the valve 38. In a similar manner, a valve 60 is located within the by-pass line 52 adjacent faucet 40. Also a valve 62 is located within the line 54 in close proximity to the faucet 42. The main by-pass line 56 is interconnected to the connecting line 12 which is located between the pump 14 and the reservoir 10.

Referring particularly to FIG. 2 of the drawing, the valve 58 is shown in greater detail. It is to be understood that the valves 58, 60 and 62 will be substantially identical in construction and in all probability will be essentially similar in construction to the faucets previously mentioned. The inlet portion 55 of the by-pass line 50' which is connected to the branch line 44 is fixedly mounted within housing 64 of the valve 58. The line 50' communicates with conduit 66 in the housing 64. The inlet conduit 66 can either be closed or open by a plunger 68. The plunger 68 is connected to a head 70 which is screw threadingly retained within the housing 64. A handle 72 is secured to the head 70 and is adapted to rotatably move the plunger within the housing 64. It can be seen that by activating the handle 72 the plunger 68 can be moved either way from the conduit 66 thereby permitting water to pass therethrough, or it can be applied against the conduit 66 thereby preventing water from passing therethrough.

With the plunger 68 moved away from the conduit 66, water is permitted to pass through the conduit 66 and into the outlet portion of the by-pass portion 50. The outlet portion of the by-pass line 50 is connected through outlet conduit 74 located within the housing 64.

The operation of the apparatus of this invention is as follows: Let it be assumed that a person is located in the area of the kitchen sink fixture 30 and desires the use of hot water. It is to be understood that similar operational features would be employed if a person were in the area of the shower fixture 32 or the wash basin fixture 34. The person first rotates the handle 72 so as to move plunger 78 away from the inlet conduit 66. As a result, hot water is permitted to pass through the branch conduit 44 into the inlet by-pass conduit 50', through the inlet conduit 66, through the outlet conduit 74 and into the by-pass line 50. The water then is conducted through the by-pass line 50 into the connecting line 12 and is to be repumped by the pumping apparatus 14 into the water heater 20. The person is to maintain this valve 58 in the open position until by sense of feel he realizes that hot water is being supplied through the valve 58. At that time the person then closes the valve 58 and then activates faucet 38, thereby obtaining hot water instantly in the area of the fixture 30. Therefore, there should be no waste of water which is supplied to the drain within the fixture 30.

A main advantage of this invention is that the capacity of the recreational vehicle holding tank is not used up as quick as a vehicle without this invention. Besides decreasing the capacity of the fresh water supply, the capacity of the holding tank (from the drains of the fix-

tures) is used up by the waste water when the apparatus of this invention is not employed.

What is claimed is:

1. A water conserving apparatus comprising: a limited capacity reservoir adapted to contain water; a pump connected to said reservoir to remove water therefrom and conduct the water into a water heater; a hot water supply line connected to said water heater and upstream thereof, said hot water supply line to supply heated water to an end removed from said water heater; a by-pass line connected to said hot water supply line adjacent said end, said by-pass line to return water downstream of said water heater; and a valve connected within said by-pass line, said valve being selectively manually actuatable to conduct water through said by-pass line; said pump located exteriorly of said reservoir, a connecting line located between said reservoir and said pump, said by-pass line connected to said connecting line, whereby said by-pass line returns water downstream of said pump.
2. A water conserving apparatus comprising: a limited capacity reservoir adapted to contain water; a pump connected to said reservoir to remove water therefrom and conduct the water into a water heater; a hot water supply line connected to said water heater and upstream thereof, said hot water supply line to supply heated water to an end removed from said water heater; a by-pass line connected to said hot water supply line adjacent said end, said by-pass line to return water downstream of said water heater; and a valve connected within said by-pass line, said valve being selectively actuatable to conduct water through said by-pass line; a second valve connected to said hot water supply line, said second valve being manually actuatable to conduct water exteriorly of said hot water supply line; and said first valve being located directly adjacent said second valve.
3. An apparatus as defined in claim 2 wherein: said first valve being manually actuatable.
4. An apparatus as defined in claim 3 wherein: said pump located exteriorly of said reservoir, a connecting line located between said reservoir and said pump, said by-pass line connected to said connecting line, whereby said by-pass line returns water downstream of said pump.
5. In combination with a recreational vehicle, said recreational vehicle having a limited capacity water reservoir, a pump located within said vehicle and capable of removing water from said reservoir, a water heater located within said vehicle, said pump to supply water to said water heater, a hot water supply line connected to said water heater, said hot water supply line to supply heated water to an end remote from said water heater, the conducting of water through said hot water supply line being controlled by means of a first manually actuatable valve, the improvement comprising: a by-pass line connected to said hot water supply line adjacent said end, said by-pass line to return water downstream of said water heater; and

a second valve connected within said by-pass line, said second valve being selectively actuatable to conduct water through said by-pass line; said pump located exteriorly of said reservoir, a connecting line located between said reservoir and said pump, said by-pass line connected to said connecting line, whereby said by-pass line returns water downstream of said pump.

6. In combination with a recreational vehicle, said recreational vehicle having a limited capacity water reservoir, a pump located within said vehicle and capable of removing water from said reservoir, a water heater located within said vehicle, said pump to supply water to said water heater, a hot water supply line connected to said water heater, said hot water supply line to supply heated water to an end remote from said water heater, the conducting of water through said hot water supply line being controlled by means of a first manually actuatable valve, the improvement comprising:

a by-pass line connected to said hot water supply line adjacent said end, said by-pass line to return water downstream of said water heater;

a second valve connected within said by-pass line, said second valve being selectively actuatable to conduct water through said by-pass line;

a second valve connected to said hot water supply line, said second valve being manually actuatable to conduct water exteriorly of said hot water supply line; and

said first valve located directly adjacent said second valve.

7. The combination as defined in claim 6 wherein: said pump located exteriorly of said reservoir, a connecting line located between said reservoir and said pump, said by-pass line connected to said connecting line, whereby said by-pass line returns water downstream of said pump.
